UNITED STATES PATENT OFFICE.

WILLIAM MILLER, OF DUNSTON-ON-TYNE, ENGLAND.

TABLE GAME.

1,371,704.

Specification of Letters Patent. Patented Mar. 15, 1921.

Application filed October 6, 1920. Serial No. 415,044.

To all whom it may concern:

Be it known that I, WILLIAM MILLER, a subject of the King of the United Kingdom of Great Britain and Ireland, and residing 5 at Dunston-on-Tyne, England, have invented a certain new and useful Improvement in Table Games, of which the following is a specification.

This invention relates to an improved 10 table game and is an adaptation of the well known games of curling on the ice, and bowls as played on a green.

For playing the improved game there is provided a bowl formed of disks of metal 15 or other suitable material and a spindle presenting projecting ends adapted to be gripped between the finger and thumb in the act of trundling.

In the accompanying drawing Figure 1 is 20 a vertical section of a bowl. Fig. 2 is a section at right angles to Fig. 1 showing the central disk and a helical spring. Figs. 3 and 4 and Figs. 5 and 6 are views similar to Figs. 1 and 2 and showing modifications.

Referring to Figs. 1 and 2, A and B are 25 cuffed metal disks securely fixed to the spindle D having projecting ends or pivots E adapted to be gripped between the finger and thumb in the act of trundling. Intermediate the cuffed disks A and B is a flat 30 disk C mounted on a short sleeve C' fitted to the spindle D. For example, a small hole may be drilled through the spindle D at right angles to the axis of rotation, and a 35 small helical compression spring F inserted therein to press against the sleeve of the central disk C to hold it securely in any required position by frictional contact.

The disks A and C are of exactly the same 40 diameter while the disk B is slightly less in diameter. The disk B is also distinctly marked by having one or more perforations for the purpose of indicating the inside of the bias when trundling the bowl on a 45 curved track.

In practice, the central disk C is slid against the marked disk B, and the bowl gripped between the finger and thumb.

When trundled along a table, the bowl will describe a perfectly straight path. When 50 the central disk C is slid against the unmarked disk A, the bowl will describe a curved path when trundled. Intermediate positions of the central disk give different curved paths. 55

In the embodiment shown in Figs. 3 and 4 the central movable disk of each bowl of a set of four bowls is dispensed with. One bowl comprises disks A' and B' of the same diameter for straight paths, and the marked 60 disk B' of each of the other three bowls is of slightly smaller diameter, the diameters being all different to give different curved paths.

The embodiment shown in Figs. 5 and 6 65 is a variant of that shown in Figs. 3 and 4 and is preferably of wood or like material.

What I claim is:—

1. A table bowl comprising a plurality of 70 disks and a spindle on which said disks are mounted, the ends of said spindle projecting beyond said disks, one disk being movable relatively to said spindle.

2. A table bowl comprising three disks 75 and a spindle on which said disks are mounted, the two outer disks being fixed to the spindle and the central disk being movable on said spindle but adapted to be frictionally held to said spindle.

3. A table bowl comprising disks of unequal diameter and a spindle on which said disks are mounted, the ends of the spindle forming pivotal pins at the axis of rotation. 80

4. A table bowl presenting a plurality of running surfaces of unequal diameter and a 85 spindle on which said bowl is mounted, the ends of the spindle forming pivotal pins on the axis of rotation.

In testimony whereof I have signed my name to this specification in the presence of 90 two subscribing witnesses.

WILLIAM MILLER.

Witnesses:

ISABEL ROLLO,
FLORENCE HOUSTON.
